F. W. WOLF,
CONTROLLER FOR GAS BURNERS,
APPLICATION FILED SEPT. 10, 1920.

1,385,513.

Patented July 26, 1921.

Milton Strouder.

ATTORNEYS.

UNITED STATES PATENT OFFICE.

FREDERICK W. WOLF, OF CHICAGO, ILLINOIS.

CONTROLLER FOR GAS-BURNERS.

1,385,513.

Specification of Letters Patent. Patented July 26, 1921.

Application filed September 10, 1920. Serial No. 409,352.

To all whom it may concern:

Be it known that I, FREDERICK W. WOLF, a citizen of the United States, residing at Chicago, in the county of Cook and State of Illinois, have invented new and useful Improvements in Controllers for Gas-Burners, of which the following is a specification.

This invention relates to gaseous fuel burners and its object is to provide the same with a novel and improved means for preventing waste of fuel through failure to turn off the supply when the burners are not actually in use.

The object is attained by means of a valve mechanism by which the fuel supply is partly shut off when the cooking utensil is removed from the burner, there being associated with the latter a valve actuating means which is controlled by the engagement therewith of the cooking utensil, said means operating to automatically turn on the fuel supply when the utensil is placed on the burner, and to partly shut off the supply when the utensil is removed.

25 The invention also has for its object to provide an automatic valve mechanism which enables the fuel supply to be completely shut off manually at will.

The invention consists in a combination 30 and arrangement of parts to be hereinafter described and claimed, and in order that the same may be better understood, reference is had to the accompanying drawing forming a part of this specification.

35 In the drawing, Figure 1 is a side elevation of the application;

Fig. 2 is an inverted plan view thereof;

Fig. 3 is an enlarged vertical section on 40 the line 3—3 of Fig. 2;

Fig. 4 is a view similar to the preceding but showing the parts in another position, and

Fig. 5 is an enlarged cross section on the 45 line 5—5 of Fig. 1.

Referring specifically to the drawing, 10 denotes an annular gas burner of conventional design having a supporting pipe 11 into which discharges the nozzle 12 of a 50 valve casing 13 connected to the gas-supply manifold 14.

The valve casing 13 has a longitudinal gas 55 passageway 15 which is in communication at one end with the manifold 14 and is continued through the nozzle 12. Intersecting this passageway transversely, is a chamber

16, the same being formed in the valve casing, and containing a valve in the form of a rotatable cylindrical plug 17 having a transverse port 18. When the valve 17 is turned 60 to bring the port 18 in line with the passageway 15, the gas can flow from the manifold 14 to the nozzle 12 to be discharged by the latter into the pipe 11 of the burner 10. The gas flow is shut off by turning the valve 17 65 to bring its port 18 completely out of registry with the passageway 15.

The valve plug 17 is slidable lengthwise in the chamber 16 for a purpose to be presently described, and from its ends extend 70 stems 19 and 20, respectively. The stem 19 extends to the outside of the casing 13 and its outer end is fitted with a handle 21 whereby the valve plug 17 may be rotated to turn the gas supply on or off as hereinbefore described. The valve casing 13 is fitted with a stuffing box 22 through which the valve stem 19 passes.

The stem 20 also passes out of the valve casing 13 through a stuffing box 23 fitted 80 thereto, and its projecting end passes loosely through a slot 24 in one end of a lever 25 extending beneath the pipe 11 and having at the center of the burner 10 an upstanding stem 26 passing through the latter and having at the top a cap 27 which is normally positioned a short distance above the plane of the burner top. The pipe 11 has a bracket arm or lug 28 to which the lever 25 is pivoted intermediate its ends as shown at 29. 90 To the lever 25 is fastened a leaf spring 30 which bears at its free end against the lug 28 and serves to hold the lever in such a position that the cap 27 is normally above the plane of the top of the burner 10. 95

On opposite sides of the lever 25 the stem 20 is fitted with abutments 31 and 32 between which the lever end is free to swing. These abutments are nuts, and between the abutment 31 and the outer end of the stuffing box 23 is located a spring 33, the same being coiled around the stem 20.

There is sufficient space between the inner ends of the stuffing boxes 22 and 23 to permit the valve plug 17 to slide therein as 105 hereinbefore described.

The abutments 31 and 32 will be so adjusted relative to the lever 25 that when the cap 27 is in its normal elevated position (it being so held by spring 30), the lever is out 110 of engagement with the abutment 31, and the spring 33 is holding the valve plug 17

drawn down such a distance that its port 18 is only partly registering with the gas passageway 15, with the result that the gas supply is partly shut off. If a cooking utensil 5 or other article is now placed on the burner 10, it engages the cap 27 and forces the same down, resulting in the rear end of the lever 25 swinging upwardly to engage the abutment 31, whereby the valve plug 17 is slid 10 upwardly to bring its port 18 into complete registry with the gas passageway 15, so that a full flow of gas to the burner 10 is now had. When the cooking vessel or other article is removed from the burner and the cap 15 27 the latter is free to rise and the lever 25 is restored to its normal position by the spring 30. The rear end of the lever now moves away from the abutment 31, whereupon the spring 33 draws the valve plug 17 20 down to bring its port 18 into the position where it only partly registers with the passageway 15, and hence the gas is now partly shut off.

The operation hereinbefore described results in a considerable saving of gas as the latter is not turned on full except when the burner is actually in use. At all other times the gas is partly shut off, only enough gas being admitted to the burner as will suffice 25 to keep the same lighted. The extent to which the gas is to be partly shut is readily regulated by the abutment 31 and the stuffing boxes or bushings 22 and 23. In full open position the valve plug 17 bears against the 30 inner end of the bushing 22, and in partly open position it bears against the inner end of the bushing 23. The abutment 32 limits the movement of the lever 25 in the direction it swings to elevate the cap 27.

40 The gas supply can be completely shut off by turning the plug 17 in the usual manner by means of the handle 21 until its port 18 is out of registry with the gas passageway 15, and this can be done when the 45 plug is in either the full or the partly registering positions hereinbefore described.

I claim:

1. The combination with a burner; of a fuel controlling valve therefor comprising a 50 casing having a fuel passageway and a chamber intersecting the same, a ported valve in the chamber, said valve being rotatable to bring its port into and out of registry with the fuel passageway, and also 55 slidable in the chamber to obtain a complete and a part registry of its port with the fuel passageway, an article-controlled means associated with the burner and having an operative connection with the valve for effecting the aforesaid sliding movement thereof, and means for controlling the extent of such sliding movement of the valve.

2. The combination with a burner; of a fuel controlled valve therefor comprising a 60 casing having a fuel passageway and a 65

chamber intersecting the same, a ported valve in the chamber, said valve being rotatable to bring its port into and out of registry with the fuel passageway, and also 70 slidable in the chamber to obtain a complete and a part registry of its port with the fuel passageway, stops in the chamber on opposite ends of the valve for limiting the sliding movement thereof, and an article-controlled means associated with the burner and having 75 an operative connection with the valve for effecting the aforesaid sliding movement thereof.

3. The combination with a burner; of a fuel-controlling valve therefor comprising a 80 casing having a fuel passageway and a chamber intersecting the same, a ported valve in the chamber, said valve being rotatable to bring its port into and out of registry with the fuel passageway, and also 85 slidable in the chamber to obtain a complete and a part registry of its port with the fuel passageway, a stem extending from the valve an article-controlled lever associated with the burner and having a connection with the 90 stem for effecting the aforesaid sliding movement of the valve, means for controlling the extent of such sliding movement of the valve.

4. The combination with a burner; of a 95 fuel-controlling valve therefor comprising a casing having a fuel passageway and a chamber intersecting the same, a ported valve in the chamber, said valve being rotatable to bring its port into and out of 100 registry with the fuel passageway, and also slidable in the chamber to obtain a complete and a part registry of its port with the fuel passageway, means for controlling the extent of the sliding movement of the 105 valve, a stem extending from the valve, an article-controlled lever associated with the burner, said lever having an aperture through which the valve stem loosely passes, an abutment on the valve stem engageable 110 by the lever, and a spring bearing against the abutment for sliding the valve in one direction.

5. The combination with a burner; of a fuel-controlling valve therefor comprising a 115 casing having a fuel passageway and a chamber intersecting the same, a ported valve in the chamber, said valve being rotatable to bring its port into and out of registry with the fuel passageway, and also 120 slidable in the chamber to obtain a complete and a part registry of its port with the fuel passageway, a stem extending from the valve, an article-controlled lever associated with the burner, said lever having an aperture 125 through which the valve stem loosely passes, an abutment on the valve stem engageable by the lever, a spring bearing against the abutment for sliding the valve in one direction, and stops in the valve chamber on opposite 130

ends of the valve for limiting the sliding movement thereof.

6. The combination with a burner; of a fuel-controlling valve therefor comprising a casing having a fuel passageway and a chamber intersecting the same, a ported valve in the chamber, said valve being rotatable to bring its port into and out of registry with the fuel passageway, and also slidable 5 in the chamber to obtain a complete or a part registry of its port with the fuel passageway, means for controlling the extent of

the sliding movement of the valve, a stem extending from the valve, an article-controlled lever associated with the burner, said lever having an aperture through which the valve stem loosely passes, abutments on the valve stem on opposite sides of the lever, and a spring bearing against one of the abutments for sliding the valve in one direction. 15

20 In testimony whereof I affix my signature.

FREDERICK W. WOLF.
